APPARATUS FOR USE IN CEMENT LASTING
FOOTWEAR

Jacob S. Kamborian, West Newton, Mass.

Application April 19, 1949, Serial No. 88,404

32 Claims. (Cl. 118—301)

1

This invention pertains to the lasting of footwear, more especially to end lasting, and is specifically directed to an appliance for use in depositing adhesive on the surface of the insole as a step in the operation of lasting. The end portions of a shoe are usually lasted in a bed-lasting machine. For example, for toe lasting, the machine usually comprises wipers which are first actuated by the operator to stretch the upper taut about the toe part of the last by an upward movement of the wipers while their edges are pressed against the upper material. At the conclusion of this uplasting, the wipers are held firmly in contact with the upper at about the plane of the insole while the operator removes some, at least, of the pulling-over tacks. The operator then opens out the marginal material of the upper at the toe and if there is a surplus of upper or lining material, this may be trimmed away at this time. The lasting wipers are now advanced and retracted so as to wipe in the marginal portion of the upper onto the bottom of the insole. The operator now retracts the wipers, but without withdrawing their inner edges completely from off the edges of the insole, thus leaving free the edges of the marginal portions of the upper. However, the upper is still held firmly and in stretched condition by the wipers. The operator now opens out the freed edge portion of the upper and at this time applies a suitable cement or adhesive, sometimes to the inner surface of the lasting margin and sometimes to the marginal portion of the inner sole. The preferred practice is to apply the adhesive to the marginal portion of the inner sole. After the adhesive has been applied to the marginal portion of the insole, the wipers are again advanced so as to lay the marginal portion of the upper down onto the adhesively-coated insole, the wipers then being depressed so as to apply heavy pressure to the marginal portion of the upper to insure proper adhesion.

The operation of applying the adhesive has heretofore usually been performed by means of a brush manipulated by the operator, but this mode of applying adhesive, in which the brush must be dipped into an open container for adhesive, is very wasteful; it usually results in the dripping of adhesive on the machine and on the floor; it is prone to result in daubing the exposed surface of the shoe with adhesive; it is difficult to apply adhesive of substantial viscosity by the brush method; and there is no certainty of uniformity of results, the correct amount of ad-

2

hesive and its proper location being entirely dependent upon the operator's skill and care.

The principal object of the present invention is to provide an appliance in the nature of an accessory to the end-lasting machine, whereby adhesive may be applied to the marginal portion of the end of the insole in an expeditious manner without substantial waste of the material or possibility of daubing the exterior surface of the shoe, and in such a manner that a substantially uniform coating of adhesive is applied to the marginal portion of the insole throughout that entire area which it is desired shall receive adhesive, and without requiring any particular skill on the part of the operator, and more rapidly than has heretofore been possible. A further object is to provide a novel device for applying adhesive, so designed that the adhesive is protected from the atmosphere until it has been discharged at the point of use. A further object is to provide a device for applying adhesive, which is readily portable and easily handled by the user and from which the adhesive is discharged only so long as the user desires and without substantial possibility of leakage or loss of adhesive in the intervals between successive operations. A further object is to provide a cement-applying device which, in a single operation, delivers cement around the entire end portion of the insole. A further object is to provide a cement-applying device capable of delivering cement, of quite viscous character, with sufficient rapidity to make the operation practical. A further object is to provide a cement-applying device having a receptacle for hot fluid adhesive and with provision for applying pressure to the upper surface of the adhesive within the receptacle, thereby to expedite its delivery at the point of use. A further object is to provide means operative to deliver a gob of adhesive of a predetermined shape and for spreading the gob to cover an extended area of the insole. Other and further objects and advantages of the invention will be pointed out in the following more detailed description and by reference to the accompanying drawings wherein:

Fig. 1 is a side elevation of the apparatus of the present invention showing the portable fluid container in the position which it occupies when not in actual use;

Fig. 2 is a vertical diametrical section, to larger scale than Fig. 1, showing the container for adhesive and the parts associated therewith;

Fig. 2a is a fragmentary vertical section on the same plane as Fig. 2 showing the delivery or

spreader foot, but with the bottom member and valve omitted;

Fig. 3 is a bottom view of the device shown in Fig. 2, but with certain parts omitted;

Fig. 4 is a plan view of a plate which forms the floor of a recess in the underside of the foot;

Fig. 5 is a plan view of a resilient closure member normally operative to prevent leakage of adhesive from the delivery orifice;

Fig. 6 is a fragmentary view, on a plane similar to that of Fig. 2, but to larger scale, and illustrating a modified form of the delivery foot, certain parts being omitted;

Fig. 7 is a plan view of the bottom member of the adhesive container illustrated in Fig. 6;

Fig. 8 is a bottom view of the bottom member of the container of Fig. 6;

Fig. 9 is a fragmentary bottom view of the delivery foot of the device of Fig. 6 with the floor plate and valve member omitted;

Fig. 10 is a plan view of the valve member of the device of Fig. 6;

Fig. 11 is a plan view of the floor block for the delivery foot of the device of Fig. 6;

Fig. 12 is a fragmentary vertical section, in the same plane as Fig. 6, but to larger scale, showing the delivery foot with its valve member and floor block assembled, and with the foot arranged in operative position with relation to a shoe insole;

Fig. 13 is a fragmentary bottom view of a shoe insole (assembled with the upper of the shoe) and showing the shape of the gob of adhesive delivered by the apparatus of the present invention; and

Fig. 14 is a view similar to Fig. 16 but showing how the original gob of adhesive may be spread over a larger area of the insole by the action of the delivery or spreader foot.

The apparatus of the present invention is designed for use in performing a step in the end lasting of shoes by the use of an end-lasting machine, the latter being of any desirable or conventional type. For convenience in description, the operation is herein outlined as applied to the cement lasting of the toe portion of a shoe, but without limitation to this specific use of the apparatus. Desirably the portable fluid container and associated parts of the present apparatus is so supported that the operator may apply it to the shoe without being obliged to sustain its entire weight, although with sufficient freedom of movement to enable it to perform its desired function. However, it is not essential that the device be thus supported, since it may be entirely free from other parts and during intervals between successive uses may be rested upon any suitable support.

As illustrated in Fig. 1, there is provided a stand 1 having a heavy base B, which may be a casting, and which may be bolted to the floor in convenient proximity to the end-lasting apparatus. A vertical rod or length of rigid tubing 2 is fixed in the base B and at a convenient height is provided with a fixed collar 3 which forms a support for a collar 4 which is rotatable on the rod 2, and to which is secured one end of rigid arm 5 extending substantially horizontally to the desired distance from the rod 2 and which, as here illustrated, is bent at 6 to provide the upwardly inclined brace member 7, whose upper end is secured to a second collar 8 which turns freely on the rod 2. The arm 5 constitutes the immediate support for the adhesive-applying device 9 of the present invention which, as here

illustrated, is suspended from the arm 5 by means of an extensible coiled spring 10. This spring is of sufficient length and flexibility so that, although sustaining the weight of the dispensing device when the latter is not in use, nevertheless permits the dispensing device to be moved into operative relation to a shoe disposed in the lasting machine in readiness to have the upstanding toe portion of the lasting margin wiped down onto the insole.

The applying device 9 is here shown (Fig. 2) as comprising a length of cylindrical tubing 11, screw-threaded at its upper end for the reception of an internally screw-threaded annulus 12 which, when assembled with the member 11, forms, in effect, a radial flange at the upper end of the latter. The tube 11 is also internally threaded at its lower end for engagement with an internally screw-threaded boss 13 forming an integral portion of the bottom member 14. This bottom member may be a casting and, as here illustrated, is of substantial vertical thickness, as compared with the thickness of the tube 11. This heavy bottom member is advantageous when a thermoplastic adhesive is used, since it serves to conduct heat from the heating units to the actual point of deposit of the adhesive, thus keeping the adhesive fluid in all of the passages leading to the delivery orifice. The bottom member 14 is provided with a rigid extension 15 at one side, herein referred to as the delivery or spreader foot nozzle, this extension 15 having a curved outer edge 16 of such shape and dimensions that said edge may be fitted within the upstanding lasting margin of the shoe upper at the toe end of the shoe. The underside of the foot 15 is provided with a recess or cavity 17 (Fig. 3) substantially segmental in plan view and open at the underside of the foot and which communicates, by means of a passage 18, with the interior chamber 19 of the adhesive container defined by the tube 11 and the bottom member 14.

As shown in Fig. 2a, the upper wall of the recess 17 is so shaped as to provide a substantially horizontal shoulder 17' and the vertical rear wall of the recess is provided with a slot 20. A boss 17b projects down at the center recess 17. The rear edge of a floor plate 20a (Figs. 3 and 4), which may be of thin sheet steel or the like and which is of segmental shape, having the curved forward edge 22, is fitted within the slot 20. The forward edge 22 of this floor plate 20a is curved to substantially the same curvature as the inner surface 22a of the lower part of the recess 17, said surface 22a being substantially concentric with the outer surface 16 of the foot, but of lesser radius, the edge 22 being spaced from the surface 22a to define a narrow delivery orifice which is of substantially U-shape or horseshoe shape in plan view. A valve member 23 of thin, flexible, resilient material, such as spring steel, and which has a contour generally similar to that of the floor plate 20a is arranged immediately above the floor plate and, together with the floor plate, is held in assembled but removable relation to the foot by means of a bolt 26 having a knurled head and which extends down through an opening 26a in the boss 17b and through openings in the valve member and floor plate, and which has screw-threaded engagement with a nut 27 disposed beneath the closure plate. To provide room for the nut, the central parts of the floor plate and valve member are upwardly dished, as shown in Fig. 3. Normally the curved edge portion of the valve member 23

resiliently engages the shoulder 17', thus preventing escape of fluid from the upper part of the chamber 17 outwardly through the orifice between the edge 22 of the bottom plate and the inner surface 22^a of the foot. However, the valve member 23 is sufficiently flexible so that if the fluid pressure within the chamber 17 exceeds a predetermined amount, the marginal portion of the valve member will flex downwardly and away from shoulder 17', thus providing communication between the chamber 17 and the delivery orifice.

To decrease the weight of the bottom member 14 the latter may be provided with a recess 28 at its underside, although this is not essential. The cover member 29 of the container is removably connected airtight to the annulus 12 by bolts 30 having knurled heads so that they may readily be withdrawn and the cover removed to facilitate the introduction of adhesive into the chamber.

Mounted on the cover 29 (Fig. 2) or integral therewith is a valve casing 31 which may be a casting or a length of bar stock. As here illustrated, this casing is a part separate from the cover 29 and secured to the latter by a bolt having a portion 32 which has threaded engagement with a transverse opening in the casing 31, and which has a conically shaped head portion 33 which seats in an opening of complementary shape in the cover 29 so as to provide a leaktight connection between the cover and the valve casing. As shown in Figs. 1 and 2, the casing 31 has an upstanding lug 31^a having a transverse hole 31^b which receives a bolt by means of which a shackle 31^c is attached to the valve casing. The lower end of spring 10 is attached to the shackle 31^c.

The valve casing 31 has a horizontally extending bore, the left-hand portion of which is enlarged and internally screw-threaded for the reception of a screw-threaded nipple 34 forming a part of a plug 35 provided with internal screw threads at 36 for the reception of a pipe fitting to which is connected one end of a flexible tube H (Fig. 1) extending to a source of compressed air, for example, an air pump or storage tank.

The bore in the valve casing 31 comprises an intermediate enlargement 37 forming a valve chamber, this chamber having the conical end wall 39 forming a seat for the ball valve 38. This ball valve is normally kept seated by the air pressure in the chamber 37.

A valve actuating rod 42 is arranged to slide in a portion 40 of the bore in the valve casing 31. This rod 42 is of substantially less diameter than the portion 40 of the bore. One end of the rod is opposed to the valve 38 and at its other end is opposed to a ball 43, located within the horizontal bore in the casing 31, and which is engaged by the left-hand end (Fig. 2) of a push rod 44 which slides in an axial bore in a plug 45 having screw-threaded engagement with an enlargement of the right-hand end of the bore in the casing 31. By movement of the rod 44 to the left, as viewed in Fig. 2, the ball 43 is forced against the rod 42 and this, in turn, pushes against and unseats the valve 38, permitting compressed air to enter the chamber 40. The bolt which connects the casing 31 to the cover 29 has an axial bore 41 through which air from the chamber 40 may enter the chamber 19 so to apply pressure to the upper surface of liquid adhesive within the chamber 19.

The right-hand end of the rod 44 has a head 46 which engages the upper end 47 of a trigger lever pivoted at 48 to a handle member 49. This

handle member is rigidly secured to the right-hand end portion of the valve casing 31 and comprises a grip portion 50 and a space 51 for the accommodation of the user's fingers. The lower end 52 of the trigger lever extends down into the space 51 where it is conveniently located for engagement by the user's finger. By pressing the finger member 52, the trigger lever is swung so as to unseat the valve 38 to allow compressed air to enter the chamber 19.

Since thermoplastic adhesive is the type of adhesive best suited for use in the lasting operation, by reason of its powerful adhesion and quick setting characteristics, it is desirable to provide for heating the contents of the chamber 19. For this purpose the bottom member 14 is provided with one or more cavities for the reception of electrical heating units 53 (Fig. 3) which may be supplied with current through flexible conductors from any suitable supply. Preferably, although not necessarily, the supply of heat may be automatically controlled by a thermostat device 54 secured to the base 14 and which is designed automatically to maintain a substantially constant predetermined temperature within the chamber 19.

A slightly modified and preferred construction is illustrated in Figs. 6 to 12, inclusive. In this arrangement the bottom member 14 has a projecting portion which extends further from the wall of the container than the foot or nozzle 15 shown in the previous figures, the foot or nozzle proper (15^a) being connected to the bottom 14 by a relatively narrow neck portion N. This arrangement may be more convenient to use in dealing with shoes of certain types and, in particular, where the side lasting has already been completed. In this arrangement the foot or nozzle 15^a is of more or less segmental contour having the curved forward edge 16 like that of the foot or nozzle 15, and having a recess 170 in its undersurface, this recess having the curved forward wall 171 which is substantially concentric with the exterior surface 16 of the foot. The foot has a substantially flat bottom surface 15^b and the recess 170 communicates with a chamber 172 within the foot which in turn is connected by a passage 180 to the interior chamber 19 of the container.

A segmental closure block 173 (Figs. 8, 11, and 12) is arranged within the recess 170, this closure block having a curved forward edge 174 which is concentric with, of smaller radius than, and spaced from the wall 171 of the recess 170 so as to define a substantially U-shaped delivery orifice 175 (Figs. 8 and 12). The curved edge of the block 173 is downwardly beveled, as shown at 176, and above this block is arranged the segmental valve member 230 (Fig. 10) having the curved forward edge 250 which normally contacts the horizontal shoulder 171^a forming a portion of the upper wall of the recess 170. This valve member 230 is of thin, flexible, resilient material, for example spring steel, and is held in assembled relation with the foot 15^a and block 173 by means of removable bolts 177. Normally the spring valve member 230 closes communication between the chamber 172 and the orifice 175.

The mode of operation of the device is the same whether the device have the delivery foot or nozzle illustrated in Fig. 2 or that illustrated in Fig. 12. The operator grasps the handle of the device and, by extending the spring 10, disposes the foot so that its forward edge 16 fits within

the upstanding margin M (Fig. 12) of the shoe upper U, the latter being already assembled with the insole S upon the last L. Having placed the delivery foot or nozzle upon the insole and within the upstanding lasting margin at the toe of the shoe, the operator actuates the finger piece 52 thereby admitting compressed air to the chamber 19. Assuming that there is within the chamber 19 a body of hot fluid thermoplastic adhesive, and that this liquid adhesive fills the passages 18 (or 180) and the chamber within the heated delivery foot, the opening of the valve 38 admits a charge of compressed air into the container which immediately raises the pressure of the liquid in the chamber within the dispensing foot to a point such that the valve 23 (or 230) automatically opens and allows a portion of adhesive to be forced outwardly through the U-shaped orifice thereby depositing on the surface of the insole S a gob G of adhesive, Fig. 13, which is substantially U-shaped in contour. This gob of adhesive lies close to the outer edge of the insole, following the contour of said edge, the amount of adhesive constituting this gob depending upon the length of time which the operator holds the finger piece 52 retracted. Substantially as soon as he releases the pressure from the finger 52, the valve device 23 (or 230) automatically cuts off communication between the chamber within the dispensing foot or nozzle and the orifice so that the delivery of adhesive ceases. The operator may lift the dispensing foot directly up from the insole if he so desire, thus leaving the adhesive in the substantially U-shaped form shown in Fig. 13. On the other hand, if he so desire, he may move the dispensing foot or nozzle rearwardly while keeping it in contact with the insole, with the result that the original U-shaped gob of adhesive is spread rearwardly to form an area A (Fig. 14) of greater or lesser extent, depending upon the distance to which the foot is drawn rearwardly along the insole while in contact with the latter. As soon as the dispensing and spreading operation has been completed, the operator releases his grasp on the handle 49 and the spring 10 immediately resumes its function of suspending the device from the supporting stand, thus leaving the operator free to use both hands in the final operation of wiping in the toe portion of the lasting margin.

Since the horizontal width of the dispensing orifice is determined by the dimensions of the plates 20^a and 173, respectively, and since these plates are removable, it is possible to provide plates of different sizes for alternative use under different conditions, and which may be substituted one for another by the operator thereby to vary the size of the delivery orifice in accordance with the character of the work and in accordance with the type of adhesive employed.

By the use of this apparatus, the adhesive is kept enclosed until it is to be dispensed, thus avoiding waste of adhesive such as occurs when it is kept in an open vessel; only so much adhesive is delivered at any one time from the container as is requisite for cementing a single shoe so that there is no waste from dripping adhesive on its way from the container to the shoe as customarily occurs when a brush is employed as the applying means; there is no probable chance of daubing the upper of the shoe with adhesive or of spilling adhesive on the lasting machine or on the floor; the thermoplastic adhesive is kept at the proper temperature and without substantial waste of heat and exactly the proper amount of adhesive is applied to each shoe and at the de-

sired point without requiring any particular skill on the part of the operator.

While certain desirable embodiments of the invention have been herein disclosed by way of example, it is to be understood that the invention is broadly inclusive of any and all other modifications falling within the scope of the appended claims.

I claim:

10. Apparatus for use in applying adhesive to the marginal portion of a shoe insole as a step in the lasting operation, said apparatus comprising an air-tight container for fluid adhesive, a foot having a curved forward edge designed to fit within the upstanding lasting margin at the end of the shoe and having an undersurface designed to rest upon the insole, said foot having a single U-shaped delivery orifice in its undersurface, said orifice being concentric with the curved forward edge of the foot, a resilient valve of thin sheet metal normally effective to close the orifice, means defining a passage for conveying adhesive from the container to said orifice, and means operative to apply pressure to the fluid in the container sufficient to flex the valve and thereby permit flow of adhesive through the orifice.
20. For use in toe lasting a shoe, in combination, a rigid foot having a curved forward edge designed to fit within the upstanding lasting margin of the upper at one end of the shoe, the foot having a shallow cavity in its under surface, the forward wall of the cavity being curved concentrically with the curved forward edge of the foot, the curved wall of the cavity having a horizontal shoulder, a plate which forms a floor for the cavity, the floor plate having a curved forward edge spaced from the curved wall of the cavity to define a narrow U-shaped orifice, and a thin, flexible valve member within the cavity having its forward edge normally contacting the horizontal shoulder thereby effectively closing the orifice, and manually controllable means operative to apply force to the valve thereby to flex it away from said shoulder.
30. In combination in apparatus for applying adhesive to the marginal portion of one end of a shoe insole, a rigid foot designed to rest upon said end portion of the insole, said foot having a curved forward edge designed to fit within the upstanding lasting margin at one end of the shoe, the foot having a shallow, segmental cavity in its under surface, the forward wall of the cavity being curved concentrically with the curved forward edge of the foot, the curved wall of the cavity having a horizontal shoulder and having a horizontal slot in its rear, vertical wall, a segmental plate which forms a floor for the cavity, the plate having a curved, forward edge spaced from the curved wall of the cavity to define a narrow U-shaped orifice, and a thin, segmental valve of resilient material whose curved forward edge normally engages the horizontal shoulder of the cavity wall thereby effectively closing the orifice, and manually controllable means operative to apply force to the curved marginal portion of the valve thereby to flex it away from the shoulder so as to permit escape of adhesive through the orifice.
40. In combination in apparatus for use in toe lasting, a portable container having a handle for use in manipulating it, a stand operative to support the container when not in use, the container having extensible suspension means for attaching it to the stand, an applying foot rigidly at-
50. In combination in apparatus for applying adhesive to the marginal portion of one end of a shoe insole, a rigid foot designed to rest upon said end portion of the insole, said foot having a curved forward edge designed to fit within the upstanding lasting margin at one end of the shoe, the foot having a shallow, segmental cavity in its under surface, the forward wall of the cavity being curved concentrically with the curved forward edge of the foot, the curved wall of the cavity having a horizontal shoulder and having a horizontal slot in its rear, vertical wall, a segmental plate which forms a floor for the cavity, the plate having a curved, forward edge spaced from the curved wall of the cavity to define a narrow U-shaped orifice, and a thin, segmental valve of resilient material whose curved forward edge normally engages the horizontal shoulder of the cavity wall thereby effectively closing the orifice, and manually controllable means operative to apply force to the curved marginal portion of the valve thereby to flex it away from the shoulder so as to permit escape of adhesive through the orifice.
60. In combination in apparatus for use in toe lasting, a portable container having a handle for use in manipulating it, a stand operative to support the container when not in use, the container having extensible suspension means for attaching it to the stand, an applying foot rigidly at-
70. In combination in apparatus for use in toe lasting, a portable container having a handle for use in manipulating it, a stand operative to support the container when not in use, the container having extensible suspension means for attaching it to the stand, an applying foot rigidly at-

tached to the container, said foot having a curved forward edge designed to be fitted within the upstanding lasting margin of a shoe upper at the toe end of the latter, the foot having a single, narrow, substantially U-shaped delivery orifice concentric with the curved forward edge of the foot and closely adjacent to but spaced rearwardly from said curved edge, means for delivering air under pressure to the interior of the container, and a manually actuatable valve for admitting compressed air from the supply to the container thereby to discharge adhesive through the orifice.

5. In apparatus of the class described, in combination, an airtight portable container having a handle for use in manipulating it, a resiliently extensible suspension element for supporting the container, a rigid foot projecting from the container near its bottom, said foot having an interior chamber which communicates with the interior of the container, the foot having a curved forward edge designed to be fitted within the upstanding lasting margin of a shoe upper at the toe end of the latter, the foot having a single, narrow, substantially U-shaped delivery orifice concentric with the curved forward edge of the foot and closely adjacent to but spaced rearwardly from said edge, means for delivering air under pressure to the interior of the container, and a manually actuatable valve for admitting compressed air from the supply to the container thereby to discharge adhesive through the orifice.

6. Portable apparatus of the class described comprising a portable air-tight container for adhesive, a delivery foot rigidly attached to the container, the foot having a curved forward edge designed to fit within the upstanding lasting margin of the shoe upper and having a shallow cavity in its under surface, the forward wall of the cavity being spaced from but closely adjacent to the curved edge of the foot, a plate which forms a floor for the cavity, the plate having a curved forward edge spaced from the curved wall of the cavity to provide a narrow U-shaped orifice, means for removably connecting the floor plate to the foot, and manually actuatable means operative to increase the pressure within the container thereby to cause adhesive from the container to exude from the orifice, and means for heating the contents of the container and for heating the foot.

7. Apparatus for use in applying adhesive to the marginal portion of a shoe insole as a step in the toe lasting operation, said apparatus comprising a portable air-tight container for fluid adhesive, a foot having a curved forward edge designed to fit within the upstanding lasting margin of the shoe upper and having a shallow cavity in its under surface, the forward wall of the cavity being spaced from but closely adjacent to the curved edge of the foot, a plate which forms a floor for the cavity, the plate having a curved forward edge spaced from the curved wall of the cavity to form a narrow U-shaped orifice, means for removably securing the floor plate to the foot, means defining a passage for conveying adhesive from the container to said orifice, manually actuatable means operative to increase the pressure within the container thereby to discharge adhesive from the orifice, and means for heating the foot.

8. An appliance for use in toe lasting shoes, comprising in combination a portable, airtight container for fluid adhesive, said container having a heavy base provided with an integral projection constituting a delivery foot, the foot hav-

ing a curved forward edge designed to fit within the upstanding lasting margin of the shoe upper and having a shallow cavity in its under surface, the forward wall of the cavity being concentric with the curved forward edge of the foot, a plate which forms a floor for the cavity, the plate having a curved forward edge spaced from the curved forward wall of the cavity to provide a narrow U-shaped orifice so shaped and located as to deliver adhesive in the form of a U-shaped gob upon the marginal portion of the toe of the insole, means providing a passage leading from the container to the cavity in the foot, a thin resilient sheet metal valve member within the cavity, said valve member normally cutting off communication between the passage and the orifice but flexing in response to a predetermined fluid pressure thereby to open communication between the passage and the orifice, means for delivering air under pressure from a supply to the interior of the container, and a manually actuatable valve admitting compressed air from said supply to the container thereby to discharge adhesive through the orifice.

9. Apparatus for use in applying adhesive to the marginal portion of a shoe insole as a step in the toe lasting operation, said apparatus comprising a portable container for fluid adhesive, the container comprising a bottom of heat conducting material having a chamber therein, an electrical heating unit housed within said chamber and which is operative to heat the bottom and the adhesive within the container, the bottom comprising a delivery foot having an undersurface designed to rest upon the toe portion of the insole, and a forward edge so curved that it may be fitted within the upstanding lasting margin of the shoe upper at the toe end of the latter, said foot having a narrow delivery orifice of substantially U-shape in its undersurface, means defining a passage for conveying adhesive from the container to said orifice, means, including a manually actuatable valve, for admitting compressed air from a supply to the container thereby to discharge adhesive through the orifice.

10. In combination in apparatus designed to apply adhesive to the toe portion of the insole of a shoe prepared for lasting, a foot having a substantially flat under surface designed to rest upon the toe portion of the insole and having a curved, forward edge of a contour approximating that of the end of the insole, said foot having a delivery orifice, a portable airtight container for fluid adhesive, means for conducting adhesive from the container to the orifice, means for delivering air under pressure from a supply to the interior of the container, a valve which is normally closed by the pressure of air from said supply, and means for unseating the valve comprising a finger-actuable trigger.

11. In combination in apparatus designed to apply adhesive to the toe portion of the insole of a shoe prepared for lasting, a foot having a substantially flat under surface designed to rest upon the toe portion of the insole and having a curved forward edge of a contour approximating that of the end of the insole, said foot having a delivery orifice, a portable, airtight container for fluid adhesive, means for conducting adhesive from the container to the orifice, means for delivering air from under pressure from a supply to the interior of the container, a valve for controlling the admission of compressed air from said supply to the container, and a finger-actuable trigger for opening the valve.

12. In apparatus of the class described, in combination, an airtight, portable container having a handle for use in manipulating it, a rigid foot projecting from the container near its bottom, said foot having an interior chamber which communicates with the interior of the container, the foot having a substantially flat undersurface designed to rest upon the toe portion of the insole, said foot having a single, substantially U-shaped delivery orifice in its underside through which adhesive may be discharged from the container, a finger-actuable lever pivotally supported by the handle, and a part operable by the lever for unseating the valve thereby to allow compressed air from a supply to enter the container so as to eject adhesive from the orifice.

13. In combination, in apparatus designed to apply adhesive to the toe portion of the insole of a shoe prepared for lasting, a portable container for adhesive, said container having a bottom provided with a projecting foot having a substantially flat undersurface designed to rest upon the toe portion of the insole and having a curved, forward edge of a contour approximating that of the toe end of the insole, the container bottom having a passage leading from the interior of the container to the foot, the foot having a delivery orifice in its undersurface, a valve casing mounted on the container, a normally closed valve therein, means for connecting the valve casing to a supply of compressed air, a handle for use in manipulating the container, and a finger-operated trigger conveniently arranged for engagement by the finger while grasping the handle thereby to open the valve and admit compressed air to the container.

14. In apparatus designed to apply adhesive to the toe portion of the insole of a shoe prepared for lasting, in combination, an airtight, portable container having a handle for use in manipulating it, a rigid foot, having a substantially flat undersurface projecting from the container near its bottom, said foot having a curved, forward edge of a contour approximating that of the toe end of the insole and having an interior chamber which communicates with the interior of the container, the foot having a single, curved delivery orifice in its underside through which adhesive may be discharged from the container, a valve casing secured to the container, said casing having a connection for a flexible conductor leading from a source of compressed air and also having a passage opening into the interior of the container, a valve normally closing said latter passage, and a finger-actuable element for opening the valve thereby to admit compressed air from said source to the container for ejecting adhesive from the orifice.

15. A portable appliance for use in toe lasting, comprising in combination a portable container for adhesive, a part having therein a delivery orifice, means defining a passage leading from the container to the delivery orifice, means normally operative to prevent escape of adhesive from the orifice, means for delivering air under pressure from a supply, a manually actuable valve for admitting compressed air from said supply to the container thereby to discharge adhesive through the orifice, and means operative to heat the parts which define the delivery orifice and the passage leading thereto.

16. Portable apparatus of the class described comprising a portable, airtight container for thermoplastic adhesive, said container having a bottom and a delivery foot in heat conducting

relation to the bottom, said foot having therein a delivery orifice of substantially U-shape, means defining a passage for adhesive leading from the container to the orifice, means normally preventing adhesive from escaping from the orifice, means operative to admit compressed air to the container thereby to cause adhesive to exude from the orifice, and means to heat the bottom of the container.

17. In combination in an apparatus for delivering adhesive to the marginal portion of one end of a shoe insole, a foot having a substantially flat undersurface designed to rest upon the insole, said foot having a curved edge substantially conforming to the curvature of the end of the insole, the foot having a substantially U-shaped orifice in its undersurface, a portable, airtight container for fluid adhesive, a conduit for conveying adhesive from the container to the orifice, movable

means normally closing the orifice but which moves to orifice-opening position in response to a predetermined pressure at its inner side, means for delivering air from a supply to the interior of the container under a pressure sufficient to move the orifice-closing means to orifice-opening position, and a manually actuable valve for admitting compressed air from said supply to the container thereby to discharge adhesive through the orifice.

18. Portable apparatus of the class described comprising a portable container for thermoplastic adhesive, means for heating the container, a delivery foot, said foot having therein a delivery orifice of substantially U-shape, means defining a passage for adhesive leading from the container to the orifice, a valve normally held closed by spring action, said valve being normally operative to prevent adhesive from exuding from the orifice, means for delivering air under pressure from a supply to the interior of the container, and a manually actuable valve for admitting compressed air from the supply to the container thereby to discharge adhesive through the orifice.

19. In combination in apparatus of the class described, a foot having a curved forward edge contoured and dimensioned to fit within the upstanding last margin at the toe end of the shoe, said foot having an undersurface in which is an orifice having a curvature similar to that of said forward edge of the foot but which is spaced inwardly from said edge, a resilient closure member normally closing said orifice but which flexes in response to a predetermined pressure at its inner side thereby to open the orifice, means for delivering air under pressure from a supply to the interior of the container, and a manually actuable valve for admitting compressed air from the supply to the container thereby to discharge adhesive through the orifice.

20. In apparatus for use in toe lasting shoes, in combination, a portable, airtight container having a handle for use in manipulating it, a rigid foot having an undersurface designed to contact the toe portion of the insole of a shoe, said foot having a recess at its underside, the upper portion of the recess always communicating with the interior of the container, a part forming a floor for the recess and whose undersurface is substantially flush with the bottom of the foot, the forward edge of said floor being so spaced from the forward edge of the recess as to define a delivery orifice, and valve means normally operative to cut off communication between the upper portion of the recess and the orifice, said

valve means opening outwardly in response to a predetermined pressure within the container, and manually-actuable means for admitting compressed air to the container thereby to create such pressures therein as to cause said valve to open.

21. In apparatus for use in toe lasting shoes, in combination, a portable container having a handle for use in manipulating it, a rigid foot projecting from the container and having an undersurface designed to contact the toe portion of the insole of a shoe, said foot having a recess at its underside, the upper portion of the recess always communicating with the interior of the container, a part forming a floor for the recess and whose undersurface is substantially flush with the bottom of the foot, the forward edge of said floor being so spaced from the forward edge of the recess as to define a delivery orifice, and a resilient, flexible closure normally cutting off communication between the upper portion of the recess and the orifice.

22. In combination in apparatus of the class described, a foot having a curved forward edge designed to fit within the upstanding lasting margin at one end of the shoe, said foot having an undersurface provided with a segment-shaped cavity having its curved edge spaced from and concentric with the curved forward edge of the foot, a segmental filler block of lesser radius of curvature than the cavity so disposed within the cavity that the curved edges of the cavity and block are spaced and concentric, the undersurface of the block being substantially flush with the undersurface of the foot, the block being of lesser height than the cavity and the foot having an interior chamber which communicates at times with the space between the curved edges of the block and cavity, a closure which normally cuts off communication between said chamber and said space, and means for supplying fluid adhesive under pressure to the chamber.

23. In combination in apparatus of the class described, a foot having a curved forward edge designed to fit within the upstanding lasting margin at the toe end of the shoe, said foot having an undersurface provided with a segment-shaped cavity whose curved edge is spaced rearwardly of and substantially concentric with the curved forward edge of the foot, a segmental block disposed within the cavity, the curved edges of the block and cavity being spaced apart and concentric thereby defining between them an orifice of substantially U-shape, the curved edge of the block being downwardly beveled and the foot having an interior chamber which at times communicates with the orifice, a thin, flexible, resilient closure overlying the block and normally cutting off communication between the chamber and orifice, and means for delivering fluid adhesive to the chamber under sufficient pressure to flex the closure downwardly toward the beveled surface of the block thereby permitting ejection of adhesive from the orifice.

24. An appliance for use in toe lasting shoes comprising in combination a portable container for fluid adhesive, said appliance comprising a nozzle having a single U-shaped delivery orifice of approximately the radius of curvature of the toe end of the shoe insole, means engageable with the upstanding lasting margin of the shoe upper to locate the nozzle in fixed position relatively to the insole while adhesive is being discharged from the orifice in the form of a single curved gob, substantially conforming to the curvature of the end of the insole, and means

providing a passage through which fluid adhesive from the container may reach the nozzle orifice, the nozzle being movable rearwardly, relatively to the insole, thereby to spread the adhesive constituting said gob.

25. A manually actuable appliance for use in toe lasting a shoe, said appliance comprising a portable container for adhesive and a nozzle member fixed to the container and having a single, substantially U-shaped curved delivery orifice conforming substantially to the curvature of the toe end of the shoe to be lasted and operative to deliver a unitary U-shaped gob of adhesive substantially conforming to the contour of the forward edge of the toe portion of the insole, the delivery orifice being arranged to discharge the adhesive into direct contact with the exposed surface of the insole, and means for initiating the expulsion of adhesive from said orifice.

26. In combination in apparatus for use in depositing a single, unitary gob of adhesive upon the toe end of the insole of a shoe prepared for lasting, said apparatus comprising a portable container for adhesive, a foot fixed to the container and having a substantially flat undersurface designed to rest directly upon the toe portion of the insole, said foot having therein an interior chamber, means for conducting adhesive from the container to said chamber, means providing a floor for said chamber, the floor having therein a single substantially U-shaped orifice through which adhesive from said chamber may be extruded in the form of a unitary U-shaped gob upon the toe end of the insole of the shoe while the foot remains stationary on the insole, and means for controlling the flow of adhesive from the container to said chamber.

27. In combination in apparatus for applying a unitary gob of adhesive to the marginal portion of one end of a shoe insole, a portable container for adhesive, the container having a rigid bottom member provided a one side with a rigid laterally-extending foot whose undersurface is substantially flush with the undersurface of the bottom member, the foot being designed to rest upon said end portion of the insole, said foot having a single U-shaped curved orifice in its undersurface which communicates with the interior of the container and which substantially conforms in contour to the curvature of the edge of said end portion of the insole, a valve element, normally closing said orifice, but which opens downwardly in response to a predetermined fluid pressure acting at its upper surface, and means whereby, at will, such predetermined fluid pressure may be established within the container thereby initiating the expulsion of fluid adhesive from said orifice in a single gob while the foot remains at rest on the insole thereby to provide a curved adhesively coated area extending along the margin of the insole at the end of the latter.

28. An appliance for use in applying adhesive to the marginal portion of one end of a shoe insole preparatory to lasting, said appliance comprising a fluid tight container having a rigid bottom member provided at one side with a rigid laterally-extending foot having a substantially flat undersurface designed to rest upon said end portion of the shoe insole and to remain stationary thereon during the adhesive-applying operation, said foot having a curved edge of a radius of curvature approximating that of the edge of the toe portion of the insole, said foot having a single U-shaped curved orifice in its undersurface which communicates with the interior of the

container and which is spaced inwardly from and which is of a curvature substantially corresponding to that of said curved edge of the foot, a resiliently flexible valve normally closing said orifice and which opens downwardly in response to a predetermined fluid pressure acting upon its upper surface, and means whereby, at will, such a predetermined fluid pressure is established within the container thereby initiating the delivery of fluid adhesive through said orifice in a single gob while the foot remains at rest thereby to form a curved, adhesively coated area extending along the margin of the toe portion of the insole.

29. Apparatus for use in applying adhesive to the marginal portion of the insole of a shoe assembled with an upper upon a last in readiness for lasting, said apparatus comprising a portable container for fluid adhesive, a foot designed to rest upon the toe portion of the insole, said foot having a curved edge designed to fit within the upturned lasting margin of the shoe upper and having within it a segmental cavity, a normally fixed but removable part normally forming a floor for the cavity, said floor-forming part having a flat under surface for contact with the inner sole, one edge of the floor being so spaced from the wall of the cavity as to define a single, substantially U-shaped orifice, and means defining a passage for conveying adhesive from the container to said orifice.

30. In combination in apparatus for applying adhesive to the marginal portion of a shoe insole assembled with an upper upon a last in readiness for lasting, said apparatus comprising a nozzle having a curved, forward edge designed to fit within the upstanding lasting margin at one end of the shoe, said nozzle having a segment-shaped cavity, a normally fixed but removable segment-shaped block having a flat under surface for contact with the insole of the shoe, said block having a forward edge of lesser radius of curvature than that of the cavity and being so disposed in the cavity that the curved edge of the block is spaced from the edge of the cavity thereby defining a single curved orifice, and means for supplying fluid adhesive for delivery through said orifice.

31. In combination in apparatus for use in toe lasting, a portable container for adhesive, means for heating thermoplastic material within the container thereby to keep the adhesive fluid, a

rigid spreader designed to rest upon the toe end of the insole of a shoe, said spreader having a curved forward edge of such shape and dimensions that it may be fitted snugly within the upstanding lasting margin of a shoe upper assembled with an insole upon a last in readiness for lasting, said spreader having therein a single, narrow delivery orifice, the delivery orifice being curved to follow the curvature of the forward edge of the foot whereby the adhesive delivered from the orifice is in the form of a unitary, substantially U-shaped gob, and means comprising a manually actuatable valve for controlling the flow of adhesive from the container to the orifice.

32. In combination in apparatus of the class described, a foot having a substantially flat under surface designed to rest upon the toe portion of the insole of a shoe prepared for lasting, said foot having a curved forward edge of a contour approximating that of the end of the insole, the foot having a single delivery orifice curved to conform substantially to the curvature of the toe portion of the insole, a portable air-tight container for fluid adhesive, means for conducting adhesive from the container to the orifice, means for supplying air under pressure, and a manually actuatable valve for admitting compressed air from the supply to the container thereby to discharge adhesive through the orifice.
